UNITED STATES PATENT OFFICE.

NATHAN B. McCREARY, OF ROCKPORT, AND ALFRED T. McCREARY, OF ST. JOSEPH, MISSOURI.

DEVICE FOR SETTING TIRES ON WAGON OR OTHER WHEELS.

SPECIFICATION forming part of Letters Patent No. 398,843, dated March 5, 1889.

Application filed April 30, 1888. Serial No. 272,511. (No model.)

To all whom it may concern:

Be it known that we, NATHAN B. McCREARY and ALFRED T. McCREARY, citizens of the United States, residing, respectively, 5 at Rockport, in the county of Atchison, in the State of Missouri, and at St. Joseph, in the county of Buchanan, in the State of Missouri, have invented a new and useful Improvement in Devices for Setting Tires on Wagon and 10 other Wheels and Treating the Wheels with Oil; and we do hereby declare that the following is a full, clear, and exact description of the construction and operation of the same, reference being had to the annexed drawings, 15 and to the letters of reference marked thereon, forming a part of this specification.

The object of our invention is to provide a simple and effectual method for more securely setting wagon and other tires and rendering 20 wheels more durable.

Our invention consists of two vessels which may be constructed of sheet metal—such as tin or galvanized iron—or of any cast metal—such as cast-iron. The vessels are made seam- 25 less, and of sufficient length, width, and height to allow the fellys of a wheel to be immersed in oil put in the vessels. The vessels may be constructed somewhat in the form of boats, and should be made seamless. They may be 30 constructed with either circular or flat bottoms, or in any form that will hold the oil and permit segments of the felly to revolve through the oil or liquid.

Similar letters refer to similar parts throughout the several views.

Figure 1 in the drawings represents our device as it appears in operation with a wheel being treated with oil or other liquid. Fig. 2 is a vertical longitudinal section of our de- 40 vice. Figs. 3 and 4 represent the rests or supports used in combination with our device. Fig. 5 is a modification of our device.

A and B represent the two vessels of our apparatus or device V-shaped in cross-section. 45 Vessel A is supported by two V-shaped iron supports, C C, with turned or hooked ends catching on the upper edges of the sides of vessel B. B is supported by two rests, D D, made of iron in the form of a Roman capital 50 letter M. These rests C C and D D are made separate from the vessels, and in shipping or

moving can be packed in the vessels or elsewhere, as may be convenient, and used as occasion may require. The vessels A and B are constructed precisely alike in shape; but vessel A is about three-fourths the size of vessel B, in order to allow of its being placed within vessel B. When so placed, supported by C C, vessel A may be filled with linseed-oil or other liquid and the vacuity outside of vessel A and 55 inside of vessel B filled with water. Vessel B being elevated upon supports D D and a fire kindled under vessel B, the water in vessel B may be speedily heated. As the water thus heated covers the entire outer surface of vessel A, the oil in vessel A is quickly melted 60 and heated. When the oil is in proper condition, the wheel upon which it is desired to firmly set the tire or treat with oil may be revolved by hand, so that the felly and tire will 65 be immersed in the oil and the felly thoroughly saturated with the oil; or the hub may be suspended upon a pin placed at a sufficient distance above vessel A to allow the felly to revolve through the oil. Vessel B being V- 70 shaped, the flame underneath readily adjusts 75 itself to and may easily be made to cover the entire surface, thus quickly and equally heating the water in all parts of the vessel.

In the use of this device the oil cannot be 80 burned and the wood of the wheel cannot be charred, and vessels A and B being constructed out of oblong sheets of metal simply folded through the middle, with ends folded upward at right angles, no crevice or crack is left for 85 the leakage of either the water or oil. By this construction the danger is obviated of melting or breaking a vessel if constructed with seams of any kind, which would, if broken by heat or otherwise, allow the oil to ooze through 90 water, and be set on fire, or in which the oil or water, if boiled down below the point of contact with heat, would injure the seams of said vessel.

Vessels A and B, without changing the principle, may be constructed with flat bottom and fluted sides, the bottom being curved to the contour of a wheel, with supports C C and D D simply varied in form sufficient to support the vessels; or, in place of supports D D, legs 100 may be permanently attached to each end of vessel B.

The heat for warming the water in vessel B may be obtained with a brush or wood fire made on the ground under the same; or a trench 5 may be dug, a fire kindled in the trench, and the apparatus or device lowered to a level with the ground and top of trench; or any other method or fuel for heating may be adopted that will suit the convenience of the person using the same.

10 If any prefer, vessel A and water in vessel B may be dispensed with and the oil placed in vessel B and heated in it directly from the flame.

What we claim as our invention, and desire 15 to secure by Letters Patent, is—

In a tire-setting device, the combination, with the outer vessel, B, formed substantially

V shape in cross-section, of a vessel, as A, within said other vessel, of substantially the same shape but smaller than the same, movable 20 supports, as C, located within the vessel B, their ends resting on the edges of the same and their centers formed to conform to the shape of the under side of the vessel A, whereby the inner vessel is held in position in the 25 center of the outer vessel, and legs supporting the outer vessel, substantially as described.

N. B. MCCREARY.
ALFRED T. MCCREARY.
